UNITED STATES PATENT OFFICE.

CHARLES EDWARD HAVILAND, OF LIMOGES, FRANCE.

DESIGN FOR A PLATE OR SIMILAR ARTICLE.

SPECIFICATION forming part of Design No. 23,900, dated December 25, 1894.

Application filed November 16, 1894. Serial No. 529,060. Term of patent 14 years.

To all whom it may concern:

Be it known that I, CHARLES EDWARD HAVILAND, a citizen of the United States, residing at the city of Limoges, in the Republic 5 of France, have invented and produced a new and original Design for a Plate or Similar Article, of which the following is a specification, reference being had to the accompanying drawings, forming part thereof, and in 10 which—

Figure 1 is a top view of a plate bearing my design, and Fig. 2 is a section of a portion of same on the dotted line 2—2 of Fig. 1.

The leading feature of my design consists 15 in the new and original and ornamental form and configuration of the outer portion of the rim of the plate, as shown in the drawings forming a part of this application.

In the drawings A designates the plate, and B the rim thereof, which rim has a scalloped 20 outer edge, and along said edge the continuous raised beading *a*, at the base of which and corresponding with the outline of the rim B is the line *b*, which is practically imperceptible to the touch but is distinguishable by the eye. 25

What I claim is—

The design for a plate or similar article, substantially as shown and described.

Signed at the city of Limoges, in the Republic of France, this 25th day of October, A. D. 30 1894.

CHARLES EDWARD HAVILAND.
